UNITED STATES PATENT OFFICE.

SAMUEL M. RHOADS, OF PHILADELPHIA, PENNSYLVANIA.

HOSE-COUPING.

No. 809,746.

Specification of Letters Patent.

Patented Jan. 9, 1906.

Application filed May 20, 1905. Serial No. 261,390.

To all whom it may concern:

Be it known that I, SAMUEL M. RHOADS, a citizen of the United States of America, residing at Philadelphia, in the county of Philadelphia and State of Pennsylvania, have invented new and useful Improvements in Hose-Couplings, of which the following is a specification.

This invention relates to improvements in hose-couplings, the object of the invention being to provide a simple, effective, and reliable coupling whose parts may be quickly and conveniently connected and disconnected and will be securely held from casual dis- placement when connected, and, further, to provide a coupling having a valve which is automatically opened when the coupling-sections are engaged and closed when said sections are disengaged to prevent escape of the fluid or liquid.

The preferred embodiment of the invention is illustrated in the accompanying drawings, in which—

Figure 1 is a longitudinal section of the coupling, showing the members thereof connected with the valve in open position for the passage of the fluid or liquid. Fig. 2 is a side elevational view of the same, the members of the coupling being separated. Figs. 3 and 4 are elevational views looking toward the meeting ends of the members of the coupling. Fig. 5 is a plan view of the male member, the locking sleeve or ring being removed; and Fig. 6 is a detail longitudinal section through the head of the female member.

Referring now more particularly to the drawings, the numeral 1 designates the male and 2 the female members of the coupling, which members are respectively provided with externally-threaded serrated stems or shanks 3 and 4 for the attachment of the hose-sections thereto, the male section 1 being attached in practice to the proximal hose-section or that connected directly or closer to the source of supply of the fluid or liquid flowing through the hose.

The member 1 comprises a head 5, having a chamber or socket 6, communicating at one end with the bore of the shank and open at its opposite end and provided with an inwardly-projecting reducing-flange 7, from which extends a tubular projection 8. On the exterior of the head 5 are spaced annular flanges 9 and 10, forming supports and guide

members for a locking sleeve or ring 11, said ring being free to slide longitudinally on the head, but held from rotation thereon by a screw or stop-pin 12, projecting into a short groove or recess 13 in the flange 10, so as to permit the ring to have but a slight rotary movement. The groove 13 is open on its rear side, so as to permit the ring to have rear sliding movement, the forward movement of the ring being limited by the engagement of the screw with the front side wall of the groove or recess. Arranged within the space or chamber formed between the ring and the two flanges 9 and 10 is a coiled spring 14, which bears at one end against the flange 9 and at its opposite end against the screw 12, and guiding projections or bosses 15, formed on the ring and movable in notches 16 in the flange 10, the spring thus serving to hold the ring projected forwardly or toward the coupling end of the head 5. The ring 11 is formed at its outer or forward edge with locking projections 17, two of which are integral with the said guiding projections 15, while the tubular projection 8 is formed at a suitable distance beyond the flange 10 with locking-lugs 18, having inclined or cam-shaped inner surfaces 19.

Projecting into the socket 6 is a cylindrical valve-casing 20, provided with spaced series of ports or passages 21 arranged therearound. This casing is provided at its outer end with an outturned flange 22, which bears against the outer side of the flange 7, the casing extending through the restricted opening formed by said flange and being supported in position thereby. The head 5 and flange 7 are formed with openings for the passage of screws 23, which detachably secure the valve-casing in position and hold it from rotary movement. Mounted to turn within the casing is a cylindrical valve member 24, provided with ports 25 to register with the ports 21 in the casing and extending at its outer end beyond said casing and formed with clutch projections 26. The valve is closed at its inner end by a head 27, from which projects a stem 28, extending into the socket 6 through an opening in the inner end of the valve-casing. On the inner end of the stem is a washer 29, secured thereon by a screw 30, and arranged about the stem between said washer and the inner end of the casing is a coiled spring 31, which holds the valve from outward move-

ment and exerts sufficient resistance to prevent the same from casually turning out of adjusted position.

The female member 2 comprises a head 32, having a socket or chamber 33, provided adjacent to its inner end with an annular flange 34 to hold the flanged inner end of a packing-ring or gasket 35 in position therein. The chamber 33 is adapted to receive the tubular projection 8 on the male member 1, which projection is adapted to fit about the packing-ring or gasket 35, the inner face of the ring and outer face of the gasket being beveled or inclined to form a fluid and water tight joint when the members of the coupling are brought into engaging relation. The outer end of the head 32 is formed with notches 36 to receive and interlock with the locking projections 17 on the locking-ring 11 and is also formed with an annular groove 37 to receive the locking-lugs 18 on the tubular projection 8. The formation of the notches 36, which serve as entrances to the groove 37, causes the production of intervening and alternately-arranged projections 38, which extend inwardly and form outer walls 39 for the grooves between the notches, the inner faces of these walls being inclined or cam-shaped to coöperate with the inclined or cam-shaped inner faces 19 of the lugs 18. The outer end of the passage or bore of the stem 4 is counterbored to receive the inner end of a tubular valve-actuating member 40, which is soldered or otherwise fixedly mounted therein. The outer end of the member 40 is provided with projections 41 to interlock with the projections 26 on the valve when the members of the coupling are connected, and in said member 40 are formed outlets 42 for the passage of the water or fluid flowing through the hose, so that the same will exert pressure against the packing-sleeve or gasket 35 and hold the same pressed against the tubular projection 8, thus forming a fluid and water tight joint.

In connecting the members of the coupling the sleeve 11 is forced back to expose the locking-lugs 18 and the members fitted together in the manner shown in Fig. 1, after which one of the members is partially rotated upon the other to bring the projections 38 into locking engagement with the lugs 18, the inclined or cam surfaces of said parts serving to draw the sections closely together. This adjustment brings the notches 36 of the member 2 in position to be engaged by the projections 17 of the ring 11, which latter is then released to permit its spring to force it into locking engagement, whereby the two members of the coupling will be held from relative rotation and disconnection. When the members are coupled in the manner described, the interlocking projections upon the valve and valve-actuating member are brought into engagement, and the partial rotation of one member upon the other thereby causes the valve,

which is always closed when the sections are disconnected, to be turned until the ports in the valve and valve-casing register, thus permitting of the flow of the water or fluid through the coupling. To disconnect the coupling, the ring 11 is forced backward and one of the members rotated upon the other until the projections 38 pass out of engagement with the lugs 18 and lie in line with the spaces between the same, whereupon the members will be thrown out of locking engagement and may be readily disconnected by a relative endwise movement. The latter-named rotation of the member in disconnecting the parts of the coupling results in the valve being turned until the ports are out of register, thus cutting off the flow of the water or fluid from the section 1 to the section 2 and preventing wastage when the parts are disconnected.

Having thus described the invention, what is claimed as new is—

1. A coupling comprising interlocking sections, one of said sections having a portion to fit within the other, a gasket within the latter section disposed to form a space for the reception of said portion and to bear against the inner face thereof, interconnecting valve and valve-operating devices carried by the respective sections, and means for maintaining the valve in closed position when the sections are separated, the valve-operating section being adapted to open the valve when the sections are connected and being provided with air-passages for the escape of fluid-pressure to act upon the gasket, substantially as described.

2. A coupling comprising interlocking male and female members, the male member being provided with a projection to enter the female member, a gasket within the female member adapted to bear against said projection, a valve axially arranged within the male member, an axially arranged valve-operating device arranged within the female member, said operating device being adapted to engage and turn the valve to open or closed position when the members are connected or disconnected, the valve-operating device being provided with ports for the escape of fluid to subject the gasket at all times to fluid-pressure.

3. A coupling comprising male and female members provided with interlocking means adapted to be engaged and disengaged by a longitudinal and rotary movement of one member relative to the other member, the male member being provided with a projection to enter the female member, a valve-casing axially disposed within the male member and provided with ports, a rotary valve disposed within said casing and provided with coöoperating ports and an outer coupling end, means for maintaining the valve in adjusted position, a gasket within the female member adapted to bear against the projection on the

male member, and an axially-arranged valve-operating device disposed within the female member provided with an interlocking portion to engage the valve, and with ports for the passage of fluid to place the gasket under pressure; said valve and valve-operating device being thrown into and out of coupling engagement by the longitudinal movement of one section upon the other section and actu-

ated to open or close the valve by the rotary movement of one section upon the other section.

In testimony whereof I affix my signature in presence of two witnesses.

S. M. RHOADS.
